UNITED STATES PATENT OFFICE.

GEORGE B. HAYES, OF BUFFALO, NEW YORK, AND JOHN A. HAYES, OF BURLINGTON, NEW JERSEY; SAID GEORGE B. HAYES ASSIGNOR TO GEORGE D. HAYES, OF BUFFALO, NEW YORK.

FOUNDRY APPARATUS.

No. 870,511.

Specification of Letters Patent.

Patented Nov. 5, 1907.

Application filed June 11, 1906. Serial No. 321,143.

To all whom it may concern:

Be it known that we, GEORGE B. HAYES and JOHN A. HAYES, citizens of the United States, and respectively residents of Buffalo, Erie county, New York, and 5 Burlington, in the county of Burlington and State of New Jersey, have invented a certain new and useful Improvement in Foundry Apparatus, of which the following is a specification.

This invention relates to the formation of molds for 10 making castings, such as pipe, and has for one object the provision of means by which the workmen may change rammers, when ramming a pipe-mold or any other deep mold, with a minimum of effort and time; another object is to secure uniform results in ramming 15 such a mold; another object is to enable the rammer to work under like conditions at all stages of the operation of ramming the mold; another object is to allow the workmen to shift from one mold-flask to another with the minimum of effort and time; another object is to 20 relieve the workmen of all effort except that of guiding and controlling the action of the ramming tools; another object is to use the same apparatus in ramming molds of different sizes or diameters; other objects will appear hereinafter.

25 The invention is embodied in the apparatus illustrated in the accompanying drawings, forming part hereof, in which—

Figure 1 is an elevation, partly in section; Fig. 2 is a plan; and Figs. 3 and 4 are detail views, taken at right 30 angles to each other, of the top of the piston shown in Fig. 1.

In the drawings, the reference character 1 designates a flask of any usual form and construction, which is mounted on the turntable 2, which also may be of any 35 usual construction and operation, being shown as provided with the circular bevel rack 3, with which a bevel gear 4 meshes to drive the turntable. The pattern is in two sections or parts, as usual, the base 5 and the upright part 6, so that the upright may be drawn 40 out of the mold in the usual manner.

The reference 7 marks a hydraulic, steam, or air cylinder, and 8 marks the inlet pipe thereof; 9 is the piston of the said cylinder 7, which has rings 10 thereon, and 11 marks similar rings inside of the cylinder 7 near 45 the top thereof. The cylinder 7 and piston 9 are of lengths such that the piston may rise as far as required and yet be steady and non-bound in the cylinder, so that it may drop at once on the release of the pressure in the cylinder 7. The piston 9, at its top, which ex-

tends above that of the cylinder, has a turntable 12 mounted thereon, and the top of the turntable affords a runway for a small truck 13. The truck 13 supports a platform 14 on which the workman stands. The platform 14 overhangs, forward and back, the turntable 12 and even the edge of the pit in which the said flask 1 is placed. At the back end of the platform is an upright or riser 15, to the top of which is connected the horizontal arm 16. The arm 16 is braced up by the brace 17. The riser 15, arm 16, and brace 17 form a jib that rises and falls and turns with the platform 14 and 60 which forms a counterbalance to the workman standing at the front of the said platform.

The jib may carry one, two, or more rammers, and it is preferred to support the rammers as follows: On the jib are pulleys 18 for the cords, chains or straps 19 to 65 one end of which the rammers 20 are made fast, while to the other end of said cords, chains, or straps 19 are made fast the counterweights 21, there being a counterweight for each rammer, as will be understood, so that each rammer may be pulled down, or shoved up independently of all the other rammers. The rammers 20 are operated by any suitable power, as steam or compressed air, the tubular connections 25 for supplying the operating fluid to the cylinders 22 of the rammers 20 being supported by the jibs. It will be noted that 70 the rammers shown are operated independently of any mechanism on the jib; that is, the rammer, whether operated by steam, air or electricity, does not depend for its operation on the jib, though, for convenience, the means whereby power is conveyed to the rammer 75 may be attached to the jib. The advantage of this arrangement is that the workman standing on the platform may manipulate the rammer freely and may start, use and stop it at will and in all positions, while it permits him to know, by the "feel," how the sand is being 80 rammed and to correct any softness that he may detect in a mold. The rammers on each jib are of different 85 lengths, for the operation is that one rammer (the longest) is used to ram the sand for a certain distance, after which it is removed from the flask, and the next 90 longest rammer is used for a given distance, and so on. Thus, if there be two rammers on the jib, the platform 14 is raised half the height of the flask while the longer rammer is used (or a little more than half the height of the flask), after which the said longer rammer is run up 95 out of the flask and shoved to one side, and the other rammer is put inside the flask, and the platform 14 is then lowered to the starting point, and the ramming

continued. With three rammers per jib, the distances are a little over one-third of the height of the flask, with a higher movement of the jib to enable the rammers to be removed therefrom; and so on for other numbers of 5 rammers.

The trucks 13 are shown as running under overhangs 23 on the turntable 12, whereby they are prevented from tipping, though it is intended, as above stated, that the weight of the workman shall be balanced by 10 that of the upright or jib. Removable stops 24 prevent the trucks from running off the turntables.

Means, such as a three-way cock 26 in the pipe 8, a waste pipe 26^X, a double lever 27 for operating said cock, and chains 28, may be provided for the workmen 15 on the platforms 14 to control the rising and falling motion of the platforms and also to turn the turntables 14 from one flask to another, as indicated in Fig. 1. Or the platforms on which the workmen stand may be raised and lowered by any means, hand or power, that 20 may be suited to the purpose, and so also of the turning of the turntables.

Sand is automatically conveyed to the flasks (means not shown) and drops between the flask and the pattern, while the workmen, standing on the platforms 14, 25 hold the cylinders 22 of the rammers by the handles thereon, and also control the air or steam supply whereby the rammers are worked. The flask is revolved by the described means, and the rammers beat upon the sand, the workmen tilting and otherwise manipulating 30 the rammers to ram the sand properly in all parts of the flask or mold, while the platforms rise more or less slowly so as to enable the workmen to always hold the rammers in substantially the same relation to themselves during the whole of the operation, thus conducting 35 to a better control of the ramming and the securing of more uniform results in the formation of the mold. As the platforms 14 lift the workmen, the rammers rise with them, until the limit of motion of the platform is reached, when the workmen stop the flow of sand, run 40 their rammers up to the ends of the horizontal arms of the jibs (see dotted lines in Fig. 1), and remove them from the flasks, and place the shorter rammer in the flask, after which the platforms are lowered to their starting points, the sand is turned on, and the 45 operation is resumed. When the platforms again reach the upper limit of their motion (assuming that but two rammers are used), the short rammers are removed from the flask, and the foundry crane (not shown) is moved over the completed mold to lift out the pattern 6, and 50 place it in another flask, while the platforms 14 are turned to the adjoining flask to enable the workmen thereon to begin ramming operations therein, as indicated by the dotted lines in Fig. 2.

It is thus seen that the ramming is done in two (or 55 more) steps, so to say, during the first of which the workmen use the longer rammers and by which they ram the flask to about half its height, and during the second of which steps they use the shorter rammers and complete the ramming of the mold. Or more than two 60 rammers may be used in more than two steps without departing from the spirit of the invention or the scope of the claims herein. That is, workmen moving up and down between certain limits, are enabled, by the

use of rammers of different lengths, to ram molds, or parts of molds, located at different levels with respect 65 to said limits. In all cases, however, the workmen each retain about the same position in relation to the rammers they are using, during the entire operation, and can thus better control the ramming, since the "feel" of the tool is not interfered with or disturbed by 70 raising or lowering the arms or hands, nor yet by the rising platforms on which the men stand.

Many changes in details and substitutions of equivalents may be made without departing from the spirit of the invention or the scope of the claims hereof. 75

What we claim as new and desire to secure by Letters Patent of the United States is—

1. In foundry apparatus, the combination with a platform for workmen to stand upon, means for raising and lowering said platform, an overhead jib carried by and raised and lowered with said platform, and a rammer suspended by counterweight from said jib in position to be raised, lowered and manipulated by workmen on said platform. 80

2. In foundry apparatus, the combination of a platform 85 for workmen to stand upon, means for raising and lowering said platform, an overhead jib carried by and raised and lowered with said platform, and a plurality of rammers suspended by counterweight from said jib in position to be raised, lowered and manipulated by workmen on said 90 platform.

3. In foundry apparatus, the combination of a platform for workmen to stand upon, means for raising and lowering said platform, and a rammer suspended from said platform in position to be manipulated by workmen standing 95 on said platform and raised and lowered by said platform.

4. In foundry apparatus, the combination of a platform for workmen to stand upon, means for raising and lowering the same, means whereby said platform may be moved horizontally independently of said raising and lowering 100 means, and a rammer supported from and moved up and down horizontally with the platform in position for manipulation by the workman on the platform, whereby said rammer with operator may be supported in proper place directly over flasks of different sizes. 105

5. In foundry apparatus, the combination of a platform for workmen to stand upon, means for raising and lowering the same, an overhead jib carried by and raised and lowered with said platform, pulleys on said jib, and a rammer and a counterweight connected by a cord or the like 110 running over said pulleys.

6. In foundry apparatus, the combination of a platform for workmen to stand upon, means for raising and lowering the same, an overhead jib carried by and raised and lowered with said platform, pulleys on said jib, and rammers and counterweights connected by cords or the like 115 running on said pulleys.

7. In foundry apparatus, the combination of a platform, means for raising and lowering said platform, means whereby said platform may be moved horizontally independently 120 of a jib mounted on said platform, pulleys mounted on said jib, and a connected rammer and counterweight supported on said pulleys.

8. In foundry apparatus, the combination of a turntable, a platform thereon, means for raising and lowering 125 said turntable and platform, and a rammer supported from and raised, lowered and operated independently of said platform.

9. In foundry apparatus, the combination of a turntable, a platform thereon for workmen to stand upon, a jib connected with said platform, a rammer suspended from and movable relatively to said jib, and means for raising and lowering said turntable and platform. 130

10. In foundry apparatus, the combination of a turntable, a platform for workmen to stand upon and movable horizontally thereon, means for raising and lowering said 135

turntable and platform, and a rammer supported from said platform.

11. In foundry apparatus, the combination of a turntable, a platform movable horizontally thereon, a jib mounted on said platform, pulleys on said jib, a rammer and a counterweight connected by a cord or the like running on said pulleys, and means for raising and lowering said turntable and platform.

12. In foundry apparatus, the combination of a turntable, a platform movable horizontally thereon, overhead pulleys supported from said platform, rammers, counter-

weights, and cords running on said pulleys and connecting rammers and counterweights, with means for raising and lowering said turntable and platform.

Signed at New York city in the county of New York, 15 and State of New York this 16th day of February, A. D. 1906.
